UNITED STATES PATENT OFFICE.

ROBERT H. INGERSOLL, OF NEW YORK, N. Y.

DESIGN FOR A WATCH-CHAIN.

SPECIFICATION forming part of Design No. 22,322, dated April 4, 1893.

Application filed December 22, 1892. Serial No. 456,096. Term of patent 3½ years.

To all whom it may concern:

Be it known that I, ROBERT H. INGERSOLL, a citizen of the United States, and a resident of New York, in the county and State of New York, certify that I have invented a certain new and original Design for a Chain for Watch-Guards, Bracelets, or Similar Articles, of which the following is a specification, reference being had to the accompanying drawing, forming a part hereof.

The leading feature of my design consists of a watch chain provided with a series of parallel strands, each pair of strands being

interrupted by an annular disk bearing upon its surface a representation of a human head. 15

What I claim is—

The design for a watch chain substantially as shown and described.

In testimony of the foregoing specification I do hereby sign the same in the city of New York, county and State of New York, this 22d day of November, A. D. 1892.

ROBERT H. INGERSOLL.
